UNITED STATES PATENT OFFICE.

CLELAND DAVIS, OF ENGLEWOOD CLIFFS, NEW JERSEY.

NON-RECOIL GUN.

1,395,630.

Specification of Letters Patent. Patented Nov. 1, 1921.

Application filed November 18, 1920. Serial No. 424,980.

To all whom it may concern:

Be it known that I, CLELAND DAVIS, a citizen of the United States, residing at Englewood Cliffs, in the county of Bergen 5 and State of New Jersey, have invented certain new and useful Improvements in Non-Recoil Guns; and I do hereby declare the following to be a full, clear, and exact description of the invention, such as will 10 enable others skilled in the art to which it appertains to make and use the same.

My present invention relates to improvements in non-recoil guns of the general type known as the "Davis non-recoil gun," 15 and illustrated, for example, in my Patent No. 1,108,715, granted August 25, 1914, and entitled Apparatus for firing projectiles from aircraft, and also in my Patent No. 1,108,716, also granted August 25, 1914, and 20 entitled Apparatus for firing projectiles from aircraft.

According to my present invention I provide a gun body made of a single continuous tube which is provided with a hinged 25 door at one side and near the central portion thereof, through which the loading of the projectile, the propelling charge and the counterweight is effected, together with means for firmly holding said door in place 30 and for preventing the escape of gas when the propelling charge is ignited.

My invention will be more fully understood after reference to the accompanying drawings, in which like parts are indicated 35 by similar reference symbols throughout the several views, and in which:—

Figure 1 is a perspective view of the improved gun, with the hinged door in the closed and locked position.

Fig. 2 shows a central axial section 40 through the gun body when loaded, the projectile and certain other parts being shown in elevation.

Fig. 3 shows a section along the line 3—3 45 of Fig. 2, and looking in the direction of the arrows; and

Fig. 4 is a sectional view on a much larger scale showing the means for locking the door in the closed position and for preventing 50 the escape of gas.

A represents the gun body which comprises a tube which may be either a single mass of metal as shown, or a built up structure as is well known in the ordnance art.

This tube may be of any suitable or desired 55 length. Near the central portion this tube is provided with an elongated opening A^o, at each end of which opening the tube is screw-threaded externally, as at a and a', and at one side of said opening the tube is 60 provided with one or more hinge lugs a² to which the corresponding hinge lugs b of the door B are pivotally connected as by means of the bolt C.

The door B is also screw-threaded externally as at b' to engage the internal screw threads on the screw collars D and D', each of which is preferably provided with an annular boss d, which may be gripped by the hand of the operator, and thus the collar may be conveniently rotated from the locking to the unlocked position, or vice versa. Surrounding the opening A^o the gun body is provided with a groove a^o in which the body portion of the gas check E is mounted, the gas check being provided with a resilient lip e' which projects into the groove adjacent the shoulder b^o of the door B, as shown in Fig. 4. This gas check thus effectively screens the joint between the door and 75 the gun body and prevents the escape of gas when the propelling charge is ignited, as when the gun is fired.

Opposite the opening A^o the gun body is provided with a boss a³, recessed to receive 85 the hollow plug F in which the electric primer G is secured, as shown in Fig. 2. This primer may be fired by any suitable electric firing apparatus such, for instance, as is shown in my Patent No. 1,108,714, 90 granted August 25, 1914 and entitled Aeroplane gun, and in my Patent No. 1,108,716 already referred to.

The projectile H when loaded in the gun is held against falling out by any suitable 95 stop, such as the pin I, see Fig. 2. Above the projectile the propelling charge J is placed, and above this is a counterweight K which may be held in place by the clamp screw L. The propelling charge may be put up in any 100 suitable container well known in the art, and the arrangement of the projectile, propelling charge and the counterweight are all diagrammatically shown in Fig. 2, as the details of this arrangement might be varied without departing from the spirit of my invention.

The operation of the device is as follows: Suppose the tube to be empty, the door B

swung to the open position, and the stop I to be in place, the projectile is loaded, as also the propelling charge and the counterweight, and the door is then closed and the screw 5 collars screwed to the position shown in Figs. 1 and 2, firmly locking the door in place. The clamp screw L is now inserted, clamping the counterweight in position, and the primer G, being in place, the gun is 10 ready to be fired.

While I have shown the gun body A formed of a comparatively short tube, this tube may be very materially lengthened if desired. The tube, of course, should be of 15 the desired thickness and strength to withstand the pressure of the propelling charge and yet provide a suitable factor of safety against the bursting of the gun when it is fired.

20 I have illustrated my herein described device in a more or less diagrammatic way, and it will be obvious that various modifications might be made in the construction, combination and arrangement of parts which could 25 be used without departing from the spirit of my invention; and I do not mean to limit the invention to such details except as particularly pointed out in the claims.

Having thus described my invention what 30 I claim and desire to secure by Letters Patent of the United States is:—

1. A non recoil gun comprising a tubular gun body open at both ends, and cut away at one side near its central region to form a 35 loading opening, a door in the form of a segment of a cylinder hinged to said gun body, and adapted to close said opening, and means for locking said door in place and for releasing same when desired, substantially as de- 40 scribed.

2. A non recoil gun comprising a tubular gun body open at both ends, and cut away at one side near its central region to form a loading opening, a door in the form of a segment of a cylinder hinged to said gun body, and adapted to close said opening, and movable collars mounted over said gun body for locking said door in place and for releasing same when desired.

50 3. A non recoil gun comprising a tubular gun body open at both ends, and cut away at one side near its central region to form a loading opening, a door in the form of a segment of a cylinder hinged to said gun body,

55 and adapted to close said opening, external screw threads provided in said gun body and said door adjacent the upper and lower edges of said opening, and internally threaded screw collars adapted to engage said 60 threads on said gun body and on said door, and to lock said door in the closed position, or to release same when desired, substantially as described.

65 4. A non recoil gun comprising a tubular gun body open at both ends, and cut away

at one side near its central region to form a loading opening, a door in the form of a segment of a cylinder hinged to said gun body, and adapted to close said opening, a gas check covering the joint between the 70 edges of said door and said gun body when the door is in the closed and locked position, and means for locking said door in place and for releasing same when desired, substantially as described.

75 5. A non recoil gun comprising a tubular gun body open at both ends, and cut away at one side near its central region to form a loading opening, a door in the form of a segment of a cylinder hinged to said gun 80 body, and adapted to close said opening, a gas check covering the joint between the edges of said door and said gun body when the door is in the closed and locked position, and movable collars mounted over said gun 85 body for locking said door in place and for releasing same when desired.

90 6. A non recoil gun comprising a tubular gun body open at both ends, and cut away at one side near its central region to form a loading opening, a door in the form of a segment of a cylinder hinged to said gun body, and adapted to close said opening, a gas check covering the joint between the 95 edges of said door and said gun body when the door is in the closed and locked position, external screw threads provided in said gun body and said door adjacent the upper and lower edges of said opening, and internally threaded screw collars adapted 100 to engage said threads on said gun body and on said door, and to lock said door in the closed position, or to release same when desired, substantially as described.

105 7. A non recoil gun comprising a tubular gun body open at both ends, and cut away at one side near its central region to form a loading opening, a door in the form of a segment of a cylinder hinged to said gun body, and adapted to close said opening, a 110 gas check having a body portion secured in a groove in said gun body and provided with a resilient lip covering the joint between the edges of said door and said gun body when the door is in the closed and 115 locked position, and means for locking said door in place and for releasing same when desired, substantially as described.

120 8. A non recoil gun comprising a tubular gun body open at both ends, and cut away at one side near its central region to form a loading opening, a door in the form of a segment of a cylinder hinged to said gun body, and adapted to close said opening, a gas check having a body portion secured in 125 a groove in said gun body and provided with a resilient lip covering the joint between the edges of said door and said gun body when the door is in the closed and locked position, and movable collars 130

mounted over said gun body for locking said door in place and for releasing same when desired.

9. A non recoil gun comprising a tubular gun body open at both ends, and cut away at one side near its central region to form a loading opening, a door in the form of a segment of a cylinder hinged to said gun body, and adapted to close said opening, a gas check having a body portion secured in a groove in said gun body and provided with a resilient lip covering the joint between the edges of said door and said gun body when the door is in the closed and locked position, external screw threads provided in said gun body and said door adjacent the upper and lower edges of said opening, and internally threaded screw collars adapted to engage said threads on said gun body and on said gun body and on said door, and to lock said door in the closed position, or to release same when desired, substantially as described.

10. A non recoil gun comprising a tubular gun body open at both ends, and cut away at one side near its central region to form a loading opening, a door in the form of a segment of a cylinder hinged to said gun body, and adapted to close said opening, means for locking said door in place and for releasing same when desired, and a firing device mounted in said gun body opposite said door, substantially as described.

11. A non recoil gun comprising a tubular gun body open at both ends, and cut away at one side near its central region to form a loading opening, a door in the form of a segment of a cylinder hinged to said gun body, and adapted to close said opening, movable collars mounted over said gun body for locking said door in place and for releasing same when desired, and a firing device mounted in said gun body opposite said door, substantially as described.

12. A non recoil gun comprising a tubular gun body open at both ends, and cut away

at one side near its central region to form a loading opening, a door in the form of a segment of a cylinder hinged to said gun body, and adapted to close said opening, external screw threads provided in said gun body and said door adjacent the upper and lower edges of said opening, internally threaded screw collars adapted to engage said threads on said gun body and on said door, and to lock said door in the closed position, or to release same when desired, and a firing device mounted in said gun body opposite said door, substantially as described.

13. A non recoil gun comprising a tubular gun body open at both ends, and cut away at one side near its central region to form a loading opening, a door in the form of a segment of a cylinder mounted on said gun body, and adapted to close said opening, and means for locking said door in place and for releasing same when desired, substantially as described.

14. A non recoil gun comprising a tubular gun body open at both ends, and cut away at one side near its central region to form a loading opening, a door in the form of a segment of a cylinder mounted on said gun body, and adapted to close said opening, and movable collars mounted over said gun body for locking said door in place and for releasing same when desired.

15. A non recoil gun comprising a tubular gun body open at both ends, and cut away at one side near its central region to form a loading opening, a door in the form of a segment of a cylinder mounted on said gun body, and adapted to close said opening, external screw threads provided in said gun body and said door adjacent the upper and lower edges of said opening, and internally threaded screw collars adapted to engage said threads on said gun body and on said door, and to lock said door in the closed position, or to release same when desired, substantially as described.

CLELAND DAVIS.
